UNITED STATES PATENT OFFICE.

RUDOLF E. HELLMUND, OF SWISSVALE, PENNSYLVANIA, ASSIGNOR TO WESTINGHOUSE ELECTRIC AND MANUFACTURING COMPANY, A CORPORATION OF PENNSYLVANIA.

SYSTEM OF CONTROL.

1,367,473.

Specification of Letters Patent.

Patented Feb. 1, 1921.

Original application filed June 19, 1915, Serial No. 35,166. Divided and this application filed May 6, 1919. Serial No. 295,080.

To all whom it may concern:

Be it known that I, RUDOLF E. HELLMUND, a citizen of the German Empire, and a resident of Swissvale, in the county of Allegheny and State of Pennsylvania, have invented a new and useful Improvement in Systems of Control, of which the following is a specification, this application being a division of application Serial No. 35,166, filed June 19, 1915, which has matured into Patent No. 1,303,307, granted May 13, 1919.

My invention relates to systems of control and it has special reference to the starting and acceleration of electric-railway vehicle motors and the like.

One object of my invention is to provide a system of the above-indicated character which shall be relatively simple and inexpensive in construction and efficient and reliable in operation.

More specifically stated, it is one object of my invention to provide a system for effecting series-parallel acceleration of electric-motors by means of a motor-generator set of relatively small capacity, whereby the energy losses during acceleration are reduced to a minimum.

Heretofore, it has been common practice for systems of the type under consideration to embody a plurality of accelerating resistors, thus wasting a certain amount of energy whenever the motors were started. In another less prevalent type of system, the motors of auxiliary motor-generator sets have been connected in the main circuit as "negative booster" machines to permit of a gradual increase of the voltage applied to the propelling motors as the voltages of the motors of the sets were decreased. To return a portion of the accelerating energy to the supply circuit, a generator driven by the motor of the set has customarily been employed. The latter method is materially more efficient than the resistor type of acceleration, but has the disadvantage of requiring machines of relatively large capacity, inasmuch as at the instant of starting, in particular, the negative booster has impressed upon it substantially full supply circuit voltage and carries the heavy starting current, and, moreover, the main motor current traverses the motor of the set at all times during acceleration.

According to my present invention, I pro-

vide a system embodying a motor-generator set which is connected in circuit to effect efficient acceleration of the main motors and which is, however, of relatively small necessary capacity, as hereinafter more fully set forth.

Other specific objects of my present invention will become evident from the following detailed description taken in conjunction with the accompanying drawing, wherein Figure 1 is a diagrammatic view of the main circuits of a system of control embodying my invention; Fig. 2 is a diagrammatic view of the auxiliary governing circuits for the system shown in Fig. 1; Fig. 3 is a sequence chart of well-known form for indicating the order of operation of the various controlling switches; and Fig. 4 to Fig. 7, inclusive, are simplified diagrammatic views illustrating various operating connections of my system.

Referring to Fig. 1, the system shown comprises supply-circuit conductors trolley and ground; a plurality of propelling electric motors, respectively having commutator-type armatures A1 and A2 and corresponding subdivided field windings F1 and F2; a main-circuit reversing switch RS for simultaneously reversing the electrical relations of the corresponding armatures and field windings; a motor-generator set having driving and generating armatures M and G, respectively, and shunt-connected field magnet windings MF and GF, the armature M being shown as provided with an additional series-connected field magnet winding MF1; and a plurality of actuating switches, as indicated in the sequence chart of Fig. 3, for suitably controlling the operation of the main motors and of the motor generator set, in the manner to be described.

The driving armature M of the auxiliary motor-generator set is adapted to be connected in series-relation with the main machines during the major portion of the acceleration thereof, while the generating armature G is adapted to be connected in parallel relation to one or both of the main machines, as hereinafter more fully set forth. An exciting field winding MF for the driving armature M is connected through a variable resistor R2 and a switch 122 across the supply circuit. An exciting field winding GF for the generating armature G

is similarly connected through a variable resistor R1 and a switch 46.

The auxiliary governing system that is shown in Fig. 2 comprises the necessary actuating coils for the various switches that are illustrated in Fig. 1; a battery B, a master reverser MR, and a master controller MC4 that is adapted to occupy a plurality of operative positions *a* to *u*, inclusive.

Assuming that the reversing switch RS and the master reverser MR occupy their respective forward positions and that the master controller MC4 is actuated to its initial position *a*, the operation of the system may be described as follows: a circuit is first established from one terminal of the battery B, through conductor 124, control fingers 125 and 125^a, which are bridged by contact segment 126 of the master controller, conductor 127, contact segment 128 of the master reverser, conductor 129, contact segment 130 of the reversing switch RS, conductor 131, the actuating coils of the switch LS, and conductors 132 and 133 to the opposite terminal of the battery B.

Other circuits are simultaneously established from the contact segment 126 through control fingers 134 to 140, inclusive, and conductors 141 to 147, inclusive, to the actuating coils of the switches 1, 3, 5, 7, 79, 80, 121, 122 and 123, respectively.

The motors are thus started into operation, with the armature M of the motor-generator set for an instant carrying substantially the full supply-circuit voltage, while the armature G of the set operates at a relatively low voltage, by reason of the deenergization of its field magnet winding GF. See Fig. 4.

In positions *b*, *c*, *d* and *e* of the master controller, the contact segment 126 engages control fingers 148, 149, 150 and 151, respectively, whereby the switches 46, 47, 77 and 78 are closed to effect the gradual strengthening of the field current traversing the field magnet winding GF, by short-circuiting successive sections of the resistor R1, while in positions *f*, *g*, *h* and *i* of the controller, the switches 79, 80, 121 and 122 are respectively opened by reason of the disengagement of the contact segment 126 from the corresponding control fingers, whereby the voltage of the armature M of the motor-generator set is gradually reduced to substantially zero by increasing the active circuit value of the resistor R2 and finally opening the circuit of the auxiliary field winding MF.

In position *i* of the controller, another circuit is established from contact segment 126, through control finger 132 to the actuating coil of the switch 10, whereby the series connected field magnet winding MF1 of the motor-generator set is short-circuited.

When the master controller is moved to its

position *j*, the contact segment 126 engages control finger 153, whence circuit is completed through the actuating coil of the switch 9, thereby short-circuiting the armature M of the motor-generator set. Note 70 Fig. 4. In this way, the residual magnetism of the auxiliary field winding is substantially nullified to effect a practical demagnetization of the auxiliary armature M during the period of short-circuit thereof before 75 the transition of the main machines to parallel relation, as about to be described. Arcing and similar undesirable conditions are effectively prevented during the transition period. 80

In position *k* of the master controller, the switch 1 is opened by reason of the disengagement of contact segment 126 and the control finger 134, whereby the main motors are connected in full-series relation 85 across the supply circuit.

In position 1, the contact segment 126 again engages control fingers 137, 138, 139, and 140, whereby the switches 79, 80, 121, and 122 are closed to effect full excitation of 90 the field winding MF of the motor-generator set. When the master controller is moved to position *m*, the contact segment 126 engages control finger 154, whence circuit is completed through the actuating coil of 95 the switch 2, whereby the voltage of the armature A2, which is thus connected in parallel relation with the armature G of the motor-generator set, is increased to a predetermined value somewhat above one-half of the supply-circuit voltage. See 100 Fig. 5.

In position *n* of the master controller, switches 3 and 9 are opened by reason of the disengagement of the contact segment 105 126 from the corresponding control fingers, and the motor having the armature A1 is thus temporarily excluded from circuit. However, in the succeeding position *o* of the controller, switch 1 is closed in the manner already described and switch 8 is closed by reason of the engagement of contact segment 126 with control finger 155. The previously disconnected motor is thus disposed in parallel-circuit relation with the motor, 110 having the armature A2, which has been included in circuit throughout. Note Fig. 6. It will be observed that, at this period of the main motor acceleration, the motor-generator set supplies the entire accelerating current for a short time, but, under the existing voltage conditions, approximately one-half this current will be supplied by the armature M and one-half by the armature G of the motor-generator set. 115

In positions *p*, *q*, *r* and *s* of the master controller, the switches 79, 80, 121 and 122 are respectively opened, in a manner similar to that already described, to gradually reduce the voltage of the armature M to zero. 130

In position *t*, the switch 9 is again closed, whereby the main motors are connected in mutual parallel-circuit relation to the armature G across the supply circuit, the armature M of the motor-generator set being again short-circuited. See Fig. 7.

When the master controller is moved to its final operative position *u*, the contact segment 126 engages control finger 156, whence circuits are completed through the parallel-connected actuating coils of the switches 4 and 6, and, simultaneously, the switches 5 and 7 are opened by reason of the disengagement of the contact segment 126 from the corresponding control fingers, whereby predetermined portions of each of the main field windings F1 and F2 are excluded from the main circuits to effect a further step in the acceleration of the main 20 motors, in accordance with a familiar practice.

It will be observed that, in the system just described, the maximum current traversing the armature G of the motor-generator set 25 does not exceed approximately one-half of the total main motor current at any time, or, in other words, is never more than one-half as much as the current that would be required if the main propelling motors were 30 permanently connected in parallel relation.

It should be noted that, during the acceleration of the main motors, the auxiliary field winding GF is strengthened and the weakening of the auxiliary field winding MF 35 is subsequently effected, which is the best way to prevent arcing or flashing in both of the auxiliary machines. Whenever the current traversing the auxiliary generating armature G is relatively large, the voltage 40 thereof is relatively low, so that field-flux distortion is not of material importance. However, full field strength for the armature G is obtained before the voltage thereof exceeds substantially one-half of the supply 45 circuit voltage, while substantially fifty per cent. of the current taken by the main machines traverses the armature G. Subsequently, the voltage in question increases, but, since the current decreases, there is again 50 but little danger of flashing. Consequently, the illustrated and described order of operation of the auxiliary field-controlling switches constitutes an important feature of the present system.

I do not wish to be restricted to the specific circuit connections or arrangement of parts herein set forth, as various modifications thereof may be effected without departing from the spirit and scope of my invention. I desire, therefore, that only such 60 limitations shall be imposed as are indicated in the appended claims.

I claim as my invention:

1. In a system of control, the combination 65 with a supply circuit, and a plurality

of electric motors, of an auxiliary motor-generator set, means for initially connecting said motors in series relation across the generating armature of said set, means for variably exciting the field windings of said set to vary the voltages of the armatures thereof and the accelerating voltage impressed upon the motors, means for effecting transition of the motors to mutual parallel relation to said auxiliary generating armature, and means for again variably exciting the field windings of the motor-generator set to effect further acceleration of the motors. 70

2. The method of operating a plurality of electric motors in conjunction with an auxiliary motor-generator set which consists in initially connecting the motors in series relation across the generating armature of said set, varying the voltages of said machine to effect predetermined acceleration of said 80 motors, subsequently connecting the motors in parallel relation across said auxiliary generating armature, and again varying the voltages of said machines to effect further acceleration of the motors. 85

3. The method of operating a plurality of electric motors in conjunction with an auxiliary motor-generator set which consists in initially connecting the motors in series relation across the armature of the first machine of said set, the second machine thereof being connected in series relation with the motors, increasing the voltage of said first machine and decreasing the voltage of said second machine to effect predetermined acceleration of the motors, short-circuiting said second machine-armature at a relatively low voltage, connecting the first motor in parallel relation with said first machine-armature when a predetermined voltage thereof obtains, connecting the other motor in parallel relation to the first motor, and again operating the motor-generator set to effect further motor acceleration. 95

4. In a system of control, the combination 110 with a supply circuit and a main electric motor, of an auxiliary motor-generator set, means for connecting the armature of one of the machines of said set in parallel relation to said main motor, means for connecting the armature of the second machine in series relation with the main motor, means for connecting the field windings of said machines in parallel relation across the armatures thereof, means associated with said field windings for independently varying the voltages of the respective machines from zero to a predetermined maximum value, and vice versa, to effect gradual acceleration of the main motor, and means for excluding from circuit that machine armature having zero voltage last. 115

5. In a system of control, the combination 120 with a supply circuit, and a plurality of main dynamo-electric machines, of an auxili- 125

ary motor-generator set, means for initially connecting said main machines in series relation, means for subsequently connecting the main machines in parallel relation across the armature of one of the machines of said set, means for connecting the armature of the other auxiliary machine in series relation with the main machines, and means for varying the voltages of the auxiliary armatures to vary the voltages of the main machines.

6. In a system of control, the combination with a supply circuit, and a main dynamo-electric machine, of a plurality of auxiliary 15 dynamo-electric machine armature windings connected to said supply circuit in series relation, means for initially connecting the main machine across one of the auxiliary armature windings and for subsequently 20 connecting the main machine across both auxiliary armature windings, and means for substantially demagnetizing the other auxiliary armature winding previous to said subsequent connection.

25 7. In a system of control, the combination with a supply circuit, and a main dynamo-electric machine, of an auxiliary motor-generator set connected to said supply circuit, means for initially connecting said main machine across the armature of one of the machines of said set, means for varying the voltage of the auxiliary machines to impress an increasing voltage upon the main machine to a certain stage, temporary means 30 for substantially nullifying the effect of one auxiliary armature, and means for subsequently connecting the main machine across both armatures of said set.

35 8. In a system of control, the combination with a supply circuit, and a main electric motor, of an auxiliary motor-generator set having its armatures connected to said supply circuit in series relation, means for initially connecting said motor across a certain armature of said set, means for varying the voltage of said certain armature from substantially zero to substantially supply-circuit voltage, means for substantially demagnetizing the other auxiliary armature, and 40 means for then connecting the motor across both machines of said set.

45 9. The method of operating a main electric motor in conjunction with an auxiliary motor-generator set which consists in initially connecting said motor across one of the armatures of said set, temporarily substantially demagnetizing the other auxiliary armature, and subsequently connecting the motor across both of the auxiliary armatures 50 under predetermined main - motor - voltage conditions.

60 10. The method of operating a main electric motor in conjunction with an auxiliary motor-generator set which consists in initially connecting said motor across one of

the armatures of said set, varying the voltage of the auxiliary machines to impress an increasing voltage upon the motor, substantially demagnetizing and short-circuiting the other auxiliary armature, and subsequently connecting the motor across both of the auxiliary armatures.

65 11. The method of operating a main electric motor in conjunction with an auxiliary motor-generator set having its armatures 70 connected to a supply circuit in series relation which consists in initially connecting said motor across a certain armature of said set, varying the voltage of said certain armature from substantially zero to substantially supply-circuit voltage, substantially demagnetizing and then short-circuiting the other auxiliary armature, and then connecting the motor across both machines of said set.

80 12. In a system of control, the combination with a supply circuit and a main electric motor, of an auxiliary motor-generator set, means for connecting the armature of one of the machines of said set in parallel 85 relation to said main motor, means for connecting the armature of the second machine in series relation with the main motor, means for connecting certain field windings of said machines in parallel relation across the armatures thereof, said second machine being also provided with a series-related field winding, means associated with the first-named field windings for independently 90 varying the voltages of the respective machines from substantially zero to a predetermined maximum value, and vice versa, to effect gradual acceleration of the main motor, means for short-circuiting said 95 series-related field winding, and means for then excluding from circuit said second machine armature.

100 13. In a system of control, the combination with a supply circuit, and a plurality of electric motors, of an auxiliary motor-generator set, the driving armature thereof having a series-related field winding and each auxiliary armature having a shunt field winding, means for initially connecting said 105 motors in series relation across the generating armature of said set, means for variably exciting the shunt field windings of said set to vary the voltages of the armatures thereof and the accelerating voltage impressed upon the motors, means for short-circuiting said series-related field winding 110 and then the corresponding auxiliary armature to connect the motors in full series relation, means for effecting transition of the 115 motors to mutual parallel relation to said auxiliary generating armature, and means for again variably exciting the shunt field windings of the motor-generator set to effect further acceleration of the motors.

120 14. In a system of control, the combina- 130

tion with a plurality of main dynamo-electric machines, of an auxiliary motor-generator set, means for initially connecting said main machines in series relation across a 5 certain machine of said set, means for varying the excitation of said auxiliary machines to accelerate the main machines to full series relation, and means, including a switch for connecting a point intermediate the main 10 machines to a point intermediate the auxiliary machines, for effecting transition of the main machines to mutual parallel relation to said certain auxiliary machine.

15. The method of operating a plurality

of dynamo-electric machines from series to 15 parallel relation in conjunction with a plurality of auxiliary-machine armatures respectively connected in series relation with and in parallel relation to said main machines that includes as a transitional step 20 the connection of a point intermediate the main machines to a point intermediate the auxiliary machines.

In testimony whereof, I have hereunto subscribed my name this 24th day of April, 25 1919.

RUDOLF E. HELLMUND.
